US0D1110552S

(12) **United States Design Patent** (10) **Patent No.:** **US D1,110,552 S**
(45) **Date of Patent:** **** Jan. 27, 2026**

(54) **LED MODULE**

(71) Applicant: **Wenjie Li**, Guangzhou (CN)

(72) Inventor: **Wenjie Li**, Guangzhou (CN)

(**) Term: **15 Years**

(21) Appl. No.: **29/920,288**

(22) Filed: **Dec. 8, 2023**

(30) **Foreign Application Priority Data**

Nov. 7, 2023 (CN) 202330725324.1

(51) **LOC (15) Cl.** **13-03**

(52) **U.S. Cl.**

USPC **D13/180**; D26/1

(58) **Field of Classification Search**

USPC D26/1-5, 24; D13/180

(57) **CLAIM**

The ornamental design for an LED module, as shown and described.

DESCRIPTION

FIG. 1 is a front perspective view of an LED module showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.
